13 Claims. (Cl. 122—411)

Centrifugal pumps are widely employed today for boiler feeding systems. However, these pumps have distinct disadvantages which very often affect an economic operation of such feeding systems.

The height of lift (head) of centrifugal pumps is determined by the centrifugal action of the impeller and by the transformation of the energy of the velocity of efflux into pressure energy within the impeller. To those skilled in the art it is known that considerable losses occur in centrifugal pumps through leakage, skin friction between the impeller and fluid, and unsatisfactory transformation of velocity energy into pressure. These losses in centrifugal pumps may be kept within tolerable limits when the pump is constructed for a large delivery and a small height of lift (head). If the height of lift, however, is to be large, the above mentioned losses in centrifugal pumps may only be reduced by resorting to multi-stage construction of such types of pumps. The efficiency of multi-stage centrifugal pumps for great heights of lift and a small delivery is so low that the operation of the same is not sufficiently economical for practical purposes.

In the present invention these disadvantages have been eliminated by arranging the impeller within a housing and subjecting the same to steam pressure, and by transforming the pressure of the lifted fluid into tangential velocity by means of jets arranged on the impeller. To accomplish the above the impeller consists of a hollow member provided with a plurality of jets at its circumference for the discharge of fluid lifted by its centrifugal action. The jets are arranged in a direction opposite the rotation of the impeller so that by reaction action of the discharging fluid a portion of the energy utilized for placing the fluid under pressure may be reclaimed.

The present invention further relates to centrifugal boiler feed pump systems wherein superfluous feed water, which has entered the boiler, may be discharged therefrom and utilized for controlling the admission of fresh feed water to the boiler, thereby affecting the operation of the pump.

The present invention further relates to centrifugal boiler feed systems for so-called forced circulation boilers, and includes arrangements for returning the water content of a steam-water mixture from a single pipe evaporator, to the boiler.

Further and other advantages of the present invention will become apparent from the following description and drawings, in which—

Figure 1 illustrates a centrifugal feed water pump arrangement for boilers, wherein the impeller is arranged within a housing and within which it is subjected to the steam pressure of a boiler in conjunction with which it is to be used.

Figure 2 shows an arrangement wherein the impeller of the centrifugal pump is located directly within the steam compartment of a boiler.

Figure 3 shows a centrifugal feed water pump arrangement of the type of the present invention, wherein the amount of delivery can be varied without variation of the revolutions of the pump.

Figure 4 shows an arrangement of the present invention in connection with a forced circulation boiler.

Figure 5 shows a construction similar to that of Figure 4, wherein the impellers are arranged on one shaft and in substantially the same horizontal plane.

Referring first to Figure 1, 1 indicates the impeller of the centrifugal pump which is of a construction to form a completely closed compartment provided at its circumference with a plurality of jets 4 which are arranged on the impeller in such a manner as to discharge fluid therefrom in a direction opposite to the direction of rotation of the impeller. The impeller 1 is mounted upon a shaft 2 which is hollow and utilized for the admission of fluid into the impeller compartment. Mounted on shaft 2 is also another impeller 9, which is of commercial construction. A housing 6 encloses the shaft 2 and the impellers 1 and 9 in a manner clearly shown in Figure 1, and is provided with pipe lines 7 and 10 for connecting the housing 6 with a boiler, in conjunction with which this centrifugal pump is to be used. The pipe line 7 is connected to the steam compartment of the boiler, and the impeller 1 within the compartment 6 is thereby subjected to exactly the same steam pressure as exists in the boiler.

In operating the pump described herein, the impeller 1 must be rotated at a speed so as to lift the fluid through the hollow shaft 2 into the compartment of the impeller 1 and to discharge the same therefrom through the orifice or jets 4 against the pressure within the compartment 6. The fluid or feed water enters the compartment 6 and flows toward impeller 9 which forces the same through the pipe line 10 of the housing 6 or a line connected with the same, into the boiler.

It should therefore be noted that the impeller 1

of the centrifugal pump is adapted to bring the feed water to the required pressure while the impeller 9 forces the water into the boiler, and need only overcome the resistance of the pipe line, which is connected with the pipe line 10.

The pump construction as illustrated in Figure 1 will not have the usual leakage loss of these types of centrifugal pumps, and the skin friction of the impeller is very considerably reduced because the same runs in steam and not in water. The jets 4 transform the pressure into tangential velocity, and, by arranging these jets so as to discharge the water in a direction opposite the direction of rotation of the impeller 1, discharge energy of the water is reclaimed by a reaction action upon the impeller 1. The amount of water discharged from the jets 4 is dependent upon the pressure difference between the water pressure at the circumference of the impeller 1 and the steam pressure within the compartment 6. Regulation of the quantity of water to be handled by the pump during a constant steam pressure in the boiler can therefore be effected by changing the water pressure, which is accomplished by varying the speed of rotation of the impeller upon which the water pressure is dependent.

The efficiency of placing the water under pressure in the closed propeller structure, and the reclaiming of a part of the used energy by reaction of the water discharging from the jets may be stated as follows:—

$$\eta = 0.5 + \frac{w}{2u}$$

wherein w is the tangential velocity (discharge velocity) of the water discharged from the jets 4, and u the speed of rotation of the impeller 1.

The efficiency increases with increasing tangential velocity (discharge velocity) w from 0.5 to a maximum. In view of the fact that the tangential or discharge velocity depends upon the pressure difference between the water and the steam pressure, the efficiency of the pump will be increased at higher pressure differences. The impeller 1 may therefore be preferably constructed for a considerably higher pressure than the boiler pressure.

Figure 2 shows a modification of the present invention. It will be noted from Figure 2 that the boiler 8 is provided with a dome-shaped compartment 8' within which the impeller 11' is arranged. In this form of construction a separate housing for the impeller is not necessary. The impeller 11' is mounted on hollow shaft 2, rotatively arranged within the compartment 8', while a motor or other prime mover outside of the compartment 8', or turbine 12 within the compartment 8', may be utilized for imparting rotative movement to the impeller 11'. The turbine should be arranged within the compartment 8' of the boiler in such a manner that all steam passing from the boiler must pass said turbine to thereby operate the same. The turbine wheel 65 is mounted directly upon the hollow shaft 2, and in this way the rotation is directly imparted to the same and the impeller 11'. The feed water is delivered to the pump from a storage tank which is placed at a higher elevation than the compartment 8', or another pump may be used for delivering the water to the impeller 11'. In the arrangement shown in Figure 2, feed water will be discharged into the boiler as soon as the speed of rotation of the impeller is sufficient to sub-

ject the feed water to a pressure slightly higher than the pressure within the boiler. The regulation of the delivery of this kind of pump can be effected by changing the speed of the prime mover which operates the pump. In case a turbine is used for the operation of the impeller wheel, an automatic regulation of the water supply in connection with the steam consumption may be attained because all the steam produced in the boiler 8 will pass through the turbine 12 which operates the impeller 11', and in this way the addition of fresh water may be accomplished, which is of course in a certain ratio to the steam produced, and discharged from the boiler.

In the types of centrifugal pumps referred to above, a regulation of the delivery of the pump in accordance with the steam consumption can only be effected by variation of the number of revolutions of the prime mover which operates the pump. In Figure 3, therefore, there is shown an arrangement of boiler feed pump which permits a regulation of the delivery thereof without variation of the speed of operation of the same. In this construction the impeller 1 is mounted within the steam compartment of the boiler 8 similar to the arrangement of Figure 2. However, in this case the impeller itself is divided into two chambers 11 and 16, the chamber or compartment 16 of the impeller 1 being in communication with a compartment 16' into which superfluous feed water from the boiler 8 is discharged by means of a pump 15 connected to said compartment 16' by means of a pipe line 15'.

Arranged within the boiler 8 is an overflow 18 connected with the pump 15 by means of a pipe line 18'. The impeller 1 is mounted on the hollow shaft 2, the latter being rotatably mounted within the compartment 16'.

Water is supplied to the impeller 1 from a reservoir and brought under pressure by the centrifugal action within the compartment 11 of the impeller 1 slightly above the pressure of the boiler, whereupon the water will be discharged into the boiler. Should sufficient water be supplied to boiler 8 and the water rise over the required level, it will be discharged into the member 18, pipe line 18', and pump 15. The pump 15 delivers the water through the line 15' into compartment 16' from where it enters the upper compartment 16 of the impeller 1.

From the above it will be seen that for the normal feeding operation of the pump the compartment 11 of the impeller 1 in Figure 3 is utilized. The compartment 11, however, is in communication with the compartment 16 on the periphery of the impeller. As in the compartment 16 of the impeller 1 only a pressure increase from the boiler pressure to the pressure at the periphery of the impeller 1 is necessary; another pressure increase on the periphery of the impeller will occur as soon as too much water has been fed into the boiler and has been returned by pump 15 to chambers 16' and 16 of the impeller 1, and at this time, when the limit of the maximum efficiency of the centrifugal action in the compartment 11 is exceeded, the delivery of fresh feed water is immediately interrupted. This condition is maintained until the proper water level in the boiler is obtained and no water is discharged from the boiler through 18 and 18' to pump 15, at which time the feeding of fresh water to the boiler will repeat, so that the water level within the boiler will be maintained practically constant.

Another modification of the invention is shown

in Figure 4, wherein a feed system is disclosed for feeding water into a forced circulation boiler 25. The operation of the system disclosed in Figure 4 is very similar to that disclosed in Figure 3, the only difference being that the produced steam-water mixture is forcibly returned to the compartment 16 of the impeller 1 through the pipe line 19. The moisture contained in the steam is separated by centrifugal action, and the saturated steam is supplied through a pipe line 20 to a super-heater 22. The water discharged by the impeller 1 in Figure 4 flows to a pump 23 which is mounted on the shaft 2, which also carries the impeller 1, and is forced from the same to the evaporator 25 of the forced circulation boiler.

Figure 5 shows substantially the same arrangement as seen in Figure 4, and corresponding parts have been correspondingly indicated. 20 However, the impeller of the pump 23 is mounted on a shaft 2', as is the impeller 1, and is also arranged in substantially the same horizontal plane as the impeller 1. In other words, the impeller 23' of pump 23 surrounds the impeller 1 at its circumference. In this construction the impeller 23' of pump 23 is rotated at a lower speed than the impeller 1, and both impellers are driven preferably by the same source of energy. 25 Transmission means 26 are mounted between the shaft 2 which carries the impeller 1, and shaft 2' which carries the impeller 23' of pump 23, for producing the desired speed reduction. The direction of rotation of the impellers 1 and 23' may be preferably the same, and both impellers 1 and 23' may be operated, if desired, by a back flow turbine.

Having thus described my invention, what I claim as new and desire to secure by Letters Patent of the United States, is—

40 1. A device for supplying feed water to a boiler, comprising, in combination, a housing, means for admitting steam from said boiler into the housing, a hollow rotatable impeller structure within said housing adapted to operate under the steam pressure of the boiler, devices 45 for admitting feed water to the impeller structure, a plurality of jets on said impeller structure arranged for discharging fluid therefrom upon rotation of the latter, and instrumentalities for rotating the impeller structure within the housing for lifting feed water into the impeller structure for subjecting the feed water to a pressure exceeding the steam pressure and for expelling the same into the boiler under transformation of such pressure into velocity of efflux.

2. A device of the class described for supplying feed water to a boiler under steam pressure, comprising, in combination, a closed hollow impeller structure having feed water inlet and outlet means, means for submerging the hollow impeller within the steam pressure of the boiler in such manner that the impeller is not submerged in the water in the boiler, and instrumentalities for operating said impeller structure for causing delivery of feed water thereto and expulsion thereof into the boiler at a pressure exceeding the steam pressure of the boiler.

3. A device of the class described for supplying feed water to a boiler under steam pressure, comprising, in combination, a closed hollow impeller structure having feed water inlet and outlet means, a source of feed water in communication with the inlet means of the hollow impeller structure, means for submerging the hollow impeller within the steam pressure of the boiler but ex-

cluding steam from the impeller, and instrumentalities for operating said impeller structure for causing delivery of feed water thereto and expulsion thereof into the boiler at a pressure exceeding the steam pressure of the boiler.

4. A device of the character described, comprising, in combination, a housing, a shaft within said housing, a closed hollow impeller structure on said shaft and rotatable within said housing, said impeller structure being provided with a fluid inlet opening and a plurality of fluid outlet openings, means for connecting said housing with the steam compartment of a boiler, and means for connecting the fluid inlet of said impeller with a source of feed water supply so that only feed water can enter said impeller.

5. A device of the character described, comprising, in combination, a housing, a hollow shaft within said housing, a closed hollow impeller structure on said shaft and rotatable within said housing, forming an impeller compartment in communication with the hollow shaft, a plurality of discharge jets on said impeller structure, means for establishing communication between said housing and the steam compartment of a boiler, and means for establishing communication between said impeller compartment and a source of feed water supply through said hollow shaft aforesaid so that only feed water can enter said impeller.

6. A device of the character described, comprising, in combination, a housing, a shaft, a closed hollow impeller structure on said shaft and rotatable within said housing, the impeller structure being provided with fluid inlet means at a point of relatively low circumferential speed, a plurality of jets on said impeller structure at points of relatively high circumferential speed for discharging fluid therefrom, means for establishing communication between the steam compartment of a boiler and said housing and means for connecting the fluid inlet means of said impeller with a source of feed water supply so that only feed water can enter said impeller.

7. A device of the character described, comprising, in combination, a housing, a shaft, a closed hollow impeller structure on said shaft and rotatable within said housing, the impeller structure being provided with fluid inlet means, a plurality of jets on said impeller structure arranged so as to discharge fluid therefrom in a direction opposite to the rotation of said impeller structure, means for establishing communication between the steam compartment of a boiler and said housing, and means for connecting the fluid inlet of said impeller with a source of feed water supply so that only feed water can enter said impeller.

8. Apparatus as defined in claim 6, in combination with a second centrifugal pump including a rotary impeller arranged to receive the feed water discharged from the jets of the first impeller, and means for connecting the second pump with the boiler so as to direct the feed water thereto.

9. Apparatus as defined in claim 6, in combination with a second centrifugal pump including a rotary impeller arranged coaxially in the housing and disposed in the same plane as the first impeller to receive the feed water discharged from the jets of the first impeller, and means for connecting the second pump with the boiler so as to direct the feed water thereto.

10. Apparatus as defined in claim 6, in combination with a second centrifugal pump including a rotary vane impeller arranged to receive the

feed water discharged from the jets of the first impeller, and means for connecting the second pump with the boiler so as to direct the feed water thereto.

5 11. Apparatus as defined in claim 6, in combination with a second centrifugal pump including a rotary impeller arranged to receive the feed water discharged from the jets of the first impeller, means for connecting the second pump with 10 the boiler so as to direct the feed water thereto, and means for driving said second impeller at a slower speed than the first impeller.

12. A centrifugal pump for supplying feed water to a boiler having a steam compartment comprising, in combination, a housing adapted to communicate with the boiler steam compartment, a shaft within said housing, and a closed hollow impeller structure carried by said shaft and rotatably mounted within said housing comprising 15 a plurality of compartments having restricted outlet jets at their periphery and having relatively unrestricted intercommunication, at least one of which compartments is adapted to communicate with a source of feed water supply and the

other compartment with a pressure medium for varying the pressure at the impeller jets aforesaid to effect a control of the delivery of the pump.

13. A feed water system for boilers or the like, 5 comprising, in combination, a housing adapted to communicate with the steam space of the boiler, a shaft within said housing, a closed hollow impeller structure carried by said shaft and rotatably mounted within said housing comprising a 10 plurality of compartments adapted to communicate with a source of feed water supply, said impeller structure having a plurality of restricted outlet jets at its periphery for discharging the water into the housing at a pressure greater than 15 the steam pressure therein, and said compartments having relatively unrestricted intercommunication, and means for returning superfluous feed water from the boiler to at least one of said impeller compartments for controlling the feed- 20 ing operation of the impeller responsive to the additional pressure created by the superfluous feed water within the impeller structure at the outlet jets.

RUDOLF HINGST. 25
